UNITED STATES PATENT OFFICE.

JOHN JORGENSEN, OF RACINE, WISCONSIN.

SPARK-PLUG.

1,353,593.

Specification of Letters Patent. Patented Sept. 21, 1920.

Application filed March 15, 1919. Serial No. 282,911.

To all whom it may concern:

Be it known that I, JOHN JORGENSEN, a citizen of the United States and resident of Racine, in the county of Racine and State of Wisconsin, have invented new and useful Improvements in Spark-Plugs, of which the following is a description, reference being had to the accompanying drawings, which are a part of this specification.

10 This invention relates to improvements in spark plugs.

The ordinary spark plug now in use is not provided with any means for indicating whether or not it is sparking within the cylinder of the engine to which it is connected, and in multiple cylinder engines it is somewhat difficult to quickly tell which plug is not properly performing its function.

It is one of the objects of the present invention to overcome the before mentioned objectionable features, and provide a spark plug in which visible means are provided for indicating whether or not the plug is properly doing its work.

25 A further object of the invention is to provide a spark plug having a plurality of contacts located at its end which is adapted to enter the engine cylinder so that an increased number of sparks will be provided 30 for igniting the charge within the engine.

A further object of the invention is to provide a spark plug in which a spark is visible between the return or ground electrode.

35 A further object of the invention is to provide a spark plug which is of very simple construction and may be mounted in the ordinary manner upon an ordinary internal combustion engine.

40 With the above and other objects in view the invention consists of the improved spark plug and its parts and combinations as set forth in the claims and all equivalents thereof.

45 In the accompanying drawing in which the same reference characters indicate the same parts in all of the views:

Figure 1 is a vertical sectional view of the improved spark plug taken on line 1—1 of 50 Fig. 2;

Fig. 2 is a transverse sectional view thereof taken on line 2—2 of Fig. 1;

Fig. 3 is an inverted end view of the sparking end of the plug;

55 Fig. 4 is a sectional detail view taken on line 4—4 of Fig. 3;

Fig. 5 is an inner end view of the sparking end of the plug showing a slightly modified form of sparking points; and

Fig. 6 is a vertical sectional view of a modified form of spark plug.

Referring to the drawing, the numeral 8 indicates the outer plug shell which is provided with a threaded portion 9 for connection with an engine, and also with a hexagonal portion 10 to permit the use of a wrench in threading the shell into the engine. The portion 11 of the shell extends vertically therethrough, and at its upper end portion is of larger diameter to form a shoulder 12 to receive a tubular clamping bolt 13.

The insulating member 14 preferably formed of mica or porcelain extends through the shell 8 and the tubular bolt 13, and is provided with an enlargement 14' which engages the shoulder 12. Copper washers 15 are preferably located between the enlargement 14 and the shoulder 12, and between the enlargement 14 and the tubular nut 13, in order to form a gas tight connection between the insulating member and the shell. Said tubular bolt 13 is threaded into the shell 8.

An entering electrode 16 extends through the insulating member from its upper medial portion to its lower peripheral portion, and projects slightly below the inner end of the insulating member.

The upper or outer end of the entering electrode is connected to a binding post 17 which is provided with the usual holding nut 18 and wire clamping nut 19. The insulating member is also provided with a ground or return electrode 20 which extends through the insulating member from a medial portion thereof to its inner end near its periphery. The upper end portion of this return electrode 20 is provided with an angular extension 20' which extends outwardly to the peripheral edge portion of the enlargement 14 and terminates at said periphery.

The shell 8 is provided with a conical opening 21 extending from its bore outwardly, and the annular extending end of the return electrode 20 terminates at a point centrally of the inner or smaller end of this conical opening to provide for the current of electricity returning to ground by jumping or arcing over the space between the end 21 and the casing 8, thus providing a

visible means for determining whether or not the plug is arcing or sparking at its inner end.

The inner end of the insulating member is provided with a plurality of supported 5 sparking points 22 mounted in the lower end portion of said insulating member and projecting a slight distance inwardly therefrom. Said sparking points extend around 10 the peripheral edge portion of the insulating member on opposite sides of the electrodes 16 and 20 so that the current entering the plug by means of the electrode 16 will jump the spaces between said sparking 15 points and return to ground through the return electrode 20 and the plug casing. This construction provides for a plurality of sparks at the inner end of the plug on both sides of the electrodes and also provides a 20 visible spark between the outer end of the return electrode and the plug shell 8. Furthermore, the resistance to the passage of the current caused by the gap spaces between the sparking points has a tendency to 25 increase the sparking and to keep the sparking points clean and free from carbon.

In the modified form shown in Fig. 5, the sparking points are in the form of a 30 circle of smaller pins spaced a proper distance apart to permit the current to jump from one pin to the other in completing its circuit.

The modified form shown in Fig. 6 is similar to the first mentioned form, with the 35 exception that the shell tubular end 13 is eliminated, and the holding nut 18 is adapted to hold the insulating member 14' in position within the shell member 8'. The lower end of this modified form of insulating member 14' is provided with a head 23 which bears against a washer 24 interposed 40 between said head and the inner end of the plug shell 8'. An insulating cap 25 covers the upper or outer end of the insulator and its inner end enters a recess 26 formed in 45 the plug shell 8', and said inner end engages the washer 26' interposed between said inner end and the plug shell. The binding post member 17 of this modified construction 50 extends upwardly through the cap member 25, and the holding nut 18 threaded thereon bears against the outer end of said cap member and firmly clamps the insulating member 14' within the plug shell 8'. Said binding post member 17 is provided with a 55 head 17' molded within the insulator member 14' to form a firm connection therewith. The electrodes 16 and 20 and the sparking points 22 of this modified form are substantially the same as the form shown in 60 the first form mentioned.

From the foregoing description it will be seen that the spark plug is of very simple construction, and is well adapted for the 65 purpose described, and it may be easily seen

whether or not the spark plugs are properly performing their function.

What I claim as my invention is:

1. A spark plug, comprising a tubular plug shell, an insulating member extending therethrough, means for clamping said insulating member to the plug shell, a pair of electrodes extending through the insulating member and terminating at their inner ends adjacent the inner end of the insulating member, a plurality of contact point members extending in spaced relation from one electrode to the other, said plug shell having a sight opening extending therethrough, the outer end of one of the electrodes terminating at a point close to but spaced from the walls of the plug shell forming said sight opening to form a visible supplemental spark gap therebetween, and a binding post mounted in the outer end portion of the insulating member and connected to the outer end of the other electrode. 70 75 80 85

2. A spark plug comprising a plug shell member having a tubular bore, an insulating member extending therethrough and provided with an enlargement for firmly connecting the insulating member to the plug shell member, means for clamping the enlarged portion of the insulating member to the plug shell, a pair of electrodes extending through the insulating member and terminating at their inner ends adjacent the inner peripheral edge of the insulating member, a plurality of sparking point members extending in spaced relation between the electrodes, said plug shell having a sight opening, the outer end portion of one of the electrodes terminating at a point adjacent to said sight opening but spaced from the walls of the plug shell forming said opening to form a visible supplemental spark gap therebetween, a binding post mounted in the outer end portion of the insulating member and connected to the outer end of the other electrode, and a clamping nut 90 95 100 105 110 mounted on said binding screw. 110

3. A spark plug comprising a plug shell member having a tubular shouldered bore and also having a sight opening extending approximately at right angles to said bore, an insulating member extending through the bore of the plug shell and having a medial enlargement positioned adjacent the shouldered portion of the bore, a pair of electrodes extending through the insulating member and terminating at their inner ends adjacent the peripheral portion of the inner end of said insulating member, the outer end of one of the electrodes terminating at a point adjacent to but spaced from the 115 120 125 walls of the plug casing forming the sight opening to form a visible supplemental spark gap therebetween, and a binding post mounted in the upper end portion of the insulating member and having a connection 130

with the outer end portion of the other electrode.

4. A spark plug, comprising a plug shell member having a bore and a sight opening, 5 an insulating member extending through the bore of the plug shell member, an inner electrode extending through the insulating member and terminating at its inner end adjacent a peripheral portion of the inner 10 end of the insulating member, a return electrode extending through the insulating member and terminating at its inner end adjacent a peripheral portion of the insulating member, the outer end portion of the return electrode terminating at a point adjacent to but spaced from the walls of the 15 plug shell forming the sight opening to form a visible supplemental spark gap therebetween, and a binding post mounted in the outer end portion of the insulating member and having a connection with the entering electrode.
5. A spark plug, comprising a plug shell member having a bore and a conical sight 20 opening, an insulating member extending through said bore and having an enlargement at its inner end which engages the inner end portion of the plug shell, an

insulating cap member extending over the outer end portion of said plug shell, a 30 binding post mounted in the outer end portion of the insulating member and extending through the cap member, a holding nut threaded on the binding post and engaging the cap member, an entering electrode 35 connected to the binding post and extending through the insulating member and terminating at the inner end of said insulating member adjacent a peripheral portion thereof, a return electrode member extending through the insulating member and terminating at its inner end adjacent a peripheral portion of the inner end of the insulating member, the outer end of said return electrode extending through the enlargement 40 and terminating at a point adjacent the walls forming the sight opening of the plug case to form a visible supplemental spark gap therebetween, and a plurality of plug contact members mounted on the inner end 45 portion of the insulating member and extending in spaced relation from one electrode to the other.

In testimony whereof I affix my signature.

JOHN JORGENSEN.
